UNITED STATES PATENT OFFICE.

THOMAS R. HOLLAND, OF WENATCHEE, WASHINGTON.

LIFTING JACK.

Application filed March 14, 1923. Serial No. 625,109.

To all whom it may concern:

Be it known that I, THOMAS R. HOLLAND, a citizen of the United States, residing at Wenatchee, in the county of Chelan and 5 State of Washington, have invented certain new and useful Improvements in Lifting Jacks, of which the following is a specification, reference being had to the accompanying drawings.

10 This invention relates to lifting jacks, and the object of the invention is to provide a lifting jack which is operated without the use of dogs, pawls or like devices and which may be, therefore, lifted or lowered to a very 15 slight degree and adjusted exactly to any height desired.

A further object is to provide a construction of this character wherein the jack is raised by means of a friction clutch and is 20 held in a raised position by a coacting friction clutch, the last named friction clutch having means whereby it may be expanded to exert greater or less friction upon the movable member of the clutch to thus permit the jack to be lowered at a more or less 25 rapid rate under the weight of the object.

Other objects have to do with the details 30 of construction and arrangement of parts as will appear more fully hereinafter.

35 My invention is illustrated in the accompanying drawings, wherein:—

Figure 1 is a side elevation of a lifting jack constructed in accordance with my invention;

35 Figure 2 is an end elevation thereof;

Figure 3 is another side elevation opposite to the elevation shown in Figure 1, showing in dotted lines the rack and gear connection;

40 Referring to these drawings, 10 designates the body of the jack, having the usual base or foot 11 formed integral with the body and the body being reinforced by the vertical ribs 12. Operating within the body is 45 the vertically adjustable standard 13, provided with a head 14 at its upper end formed to fit beneath the object to be lifted, this standard 13 being formed with gear teeth 15.

Passing through the body 10 or mounted 50 thereon in any suitable manner is a shaft 16, which shaft carries upon it the gear wheel 17 which engages the teeth 15 and which gear wheel projects out through an opening 18 in the side wall of the body 10. For the

55 purpose of operating the gear wheel 17 and

thereby operating the standard 15, I mount upon the shaft 16 a friction drum 19 and operating in conjunction with this drum is the sectional friction band composed, as shown, of the two sections 20 and 21, these sections 60 being pivoted to each other at 22. The section 20 is longer than the section 21 and its terminal end 23 extends tangentially to the circumference of the drum, and, as before remarked, projects beyond the adjacent 65 extremity of the section 21.

Pivoted to the section 21 at 24 is an operating lever 25 and the extremity 23 of the section 20 is also pivoted to this operating lever at 26. As illustrated, the extremity of the section 21 is bifurcated to receive the end of the operating lever 25, while the upper edge of the lever 25 is formed with spaced ears between which the extremity of the section 20 is disposed, the pin 26 70 passing through these ears and through the section 20. Inasmuch as the section 23 is pivoted to the lever 25 outward of the pivotal point 24, it is obvious that upon a depression of the free end of the lever 25 the 75 two sections of the friction band will be drawn together and have very tight frictional engagement with the drum 19. Preferably a coiled contractile spring 27 is engaged with the section 20 inward of its 80 point of pivotal engagement 26 with the lever 25, and the other end of this lever 27 is engaged with the inner end of the lever 25. A stop lug 28 is carried by the body 85 10 and projects out in the path of movement 90 of the lever 25 and constitutes a stop for this lever when drawn in one direction. Obviously when the lever 25 is drawn upward so as to engage against the stop 28, the two 95 sections of the band will be fully opened 95 and the drum will be entirely free. On the other hand, when the lever 25 is drawn downward, the sections of the band will be clamped upon the drum and will frictionally engage the same so as to clutch the drum to 100 the lever. Preferably the two sections 20 and 21 of the band are pivotally connected by a pin 22.

The opposite end of the shaft 16 carries upon it a friction drum 29 and extending 105 around this friction drum 29 is a two-section brake band, one of the sections being designated 30 and the other 31. The sections 30 and 31 are pivoted to each other by a pin 32. The section 30 is semi-circular in form and 110

at its end opposite the connection 32 is formed with an ear 33 pivoted by a pin 34 to a lever 35. This lever 35 is pivoted at 36 to the body 10. The section 31 of the band embraces a portion of the periphery of the drum, then extends tangentially downward and toward the lever 35 and is pivoted by a pin 37 to this lever 35, this point of pivotal connection being beyond the point of pivotal connection of the section 30 to the lever. A coiled compression spring 38 supported at one end in any suitable manner bears against the upper end of the lever and urges it outward.

Pivotedly mounted upon the body 10 is a cam 39 having a handle 40. This cam is eccentrically pivoted upon a pin 41 and when this cam is turned so as to cause it to bear against the lever 35 it will force the upper end of the lever 35 inward, thus reducing or breaking the frictional contact between the brake band formed of the sections 30 and 31 and the friction wheel or drum 29. When, however, the handle 40 is lowered to the position shown in Figure 1, the spring 38 will act upon the lever 35 to cause the sections of the brake band to bind upon and frictionally lock on the drum 29. It will be noted from Figure 3 that as the handle 25 is raised, assuming there is a weight on the standard, the handle 25 and the clutch members 20 and 21 will move with the drum 19 in a clockwise direction. When, however, the handle end of the clutch section 20 engages the stop 28, the stop 28 acts as a fulcrum for the lever 25 and permits this lever to be still further lifted, and this further lifting movement will act to open or separate the clutch sections 20 and 21, thus permitting the standard 13 to move downward and permitting the rotation of the drum 19 within the clutch sections, the speed of this rotation of the drum 19 being governed by the frictional resistance of the bands 20 and 21. Thus if the outer end of the lever 25 is lifted when the lever is fulcrumed upon the stop 28, the clutch sections will be entirely opened, but if it is desired to check the downward movement of the standard, the lever 25 is depressed slightly, which will cause the clutch sections to contract upon the drum, thus applying frictional resistance thereto.

With the friction clutch in the position shown in Figures 1 and 3 and the cam handle 40 down, the standard or rack 15 is raised by alternately lowering and raising the handle 25 until the standard is at the desired height. Now in order to lower the standard, the pressure on the head 14 is entirely taken from drum 29 by pressing down on the handle 25. The handle of cam 40 is then raised until the frictional engagement between drum 29 and the bands 30 and 31 is entirely relieved and then the handle 25 is

raised until it comes in contact with stop 28, thus gradually lowering the standard, and when the handle 25 comes in contact with the stop 28 a further upward pressure on the handle against the stop 28 will cause the bands 20 and 21 to open and the standard will slide down at the will of the operator and controlled by the friction of the bands 20 and 21 against the drum 19.

It will be seen that this construction gives continuous control of the load in letting the jack down and the load may be lifted or lowered to the slightest fraction of an inch, as there are no dogs or pawls which can only engage at predetermined points. The friction clutch or brake formed by the sections 30 and 31 of the drum 29 acts immediately to hold the rack bar or standard from depression and by operating the cam 39 any desired degree of frictional resistance to the lowering of the load may be secured.

While I have illustrated a form of my invention which I deem to be particularly practical, which is compact and simple, yet it is obvious that the invention might be embodied in other forms without departing from the spirit thereof as defined in the appended claims.

I claim:—

1. A lifting jack of the character described comprising a tubular base, a standard movable vertically within the base, the standard having rack teeth, a gear wheel mounted upon the base and engaging said rack teeth, a shaft upon which the gear wheel is mounted, a drum mounted upon one end of the shaft, a friction clutch operatively engaging said drum and having a lever, the clutch operating to frictionally engage the drum upon a movement of the lever in one direction but operatively disengaging from the drum upon a movement of the lever in the other direction, and frictionally operated means permitting free upward movement of the standard but locking the standard in a raised position and resisting downward movement thereof, and manually operable means for gradually releasing the frictional engagement between said frictionally operated means and the standard to permit the depression of the standard.

2. A lifting jack of the character described comprising a tubular base, a standard movable vertically within the base, the standard having rack teeth, a gear wheel mounted upon the base and engaging said rack teeth, a shaft upon which the gear wheel is mounted, a drum mounted upon one end of the shaft, a friction clutch operatively engaging said drum and having a lever, the clutch operating to frictionally engage the drum upon a movement of the lever in one direction but operatively disengaging from the drum upon a movement of the lever in the other direction, a second friction drum

carried upon said shaft, a frictional brake band surrounding the drum, a lever operatively connected to the brake band and movable in one direction to contract the brake band upon the drum and in the other direction to expand the brake band upon the drum, means normally urging the brake lever into a position to contract the brake band on the drum, and manually operable means adjustable in one direction to shift the brake lever to thereby reduce the frictional engagement between the brake band and the drum and in the other direction to permit the brake band to frictionally engage the drum.

3. A lifting jack of the character described comprising a tubular base, a toothed standard mounted for vertical movement in the base, a gear wheel mounted upon the base and engaging the standard, a shaft on which the gear wheel is mounted and extending laterally outward beyond the base, friction drums mounted upon opposite ends of the shaft, a band formed of two sections embracing one of said drums, one end of the band extending beyond the other end, a lever having pivotal engagement with the opposite ends of the band, said lever when forced downward contracting the band around the drum and when lifted releasing the grip of the band on the drum, a stop limiting the upward movement of the lever with the drum, a brake band surrounding the other drum and formed of two sections together partially embracing the drum, one end of said brake band extending beyond the other end, a lever pivoted to opposite ends of the brake band and pivoted to the base at the end opposite the brake band, a spring urging said lever in a direction to contract the brake band upon the drum, and a cam pivotally mounted upon the base and having a handle, the cam when turned in one direction bearing against the lever and urging it in a direction to expand the brake band and when turned in the other direction permitting the brake band to contract around the drum.

5. A lifting jack of the character described comprising a base, a standard vertically movable upon the base, a shaft operatively engaged with the standard, a drum mounted upon one end of the shaft, a friction clutch operatively engaging said drum and having a lever, the clutch operating to frictionally engage the drum upon a movement of the lever in one direction but operatively disengaging it from the drum upon a movement of the lever in the other direction, frictionally operated means permitting free upward movement of the standard but locking the standard in a raised position and resisting downward movement thereof, manually operable means for gradually releasing the frictional engagement between said frictionally operated means and the standard to permit depression of the standard, and a stop carried upon the base against which the lever bears when the lever has been raised to a predetermined extent, said stop preventing the further rotation of the friction clutch and lever with the corresponding drum and acting as a fulcrum whereby the lever may be turned to open the clutch and permit the downward movement of the standard.

4. A lifting jack of the character described comprising a tubular base, a toothed standard mounted for vertical movement in the base, a gear wheel mounted upon the base and engaging the standard, a shaft on which the gear wheel is mounted and extending laterally outward beyond the base, friction drums mounted upon opposite ends of the shaft, a band formed of two sections

embracing one of said drums, one end of the band extending beyond the other end, a lever having pivotal engagement to the opposite ends of the band, said lever when forced downward contracting the band around the drum and when lifted releasing the grip of the band on the drum, a stop limiting the upward movement of the lever, a brake band surrounding the other drum and formed of two sections together partially embracing the drum, one end of said brake band extending beyond the other end, a lever pivoted to opposite ends of the brake band and pivoted to the base at the end opposite the brake band, a spring urging said lever in a direction to contract the brake band upon the drum, and a cam pivotally mounted upon the base and having a handle, the cam when turned in one direction bearing against the lever and urging it in a direction to expand the brake band and when turned in the other direction permitting the brake band to contract around the drum.

5. A lifting jack of the character described comprising a base, a standard vertically movable upon the base, a shaft operatively engaged with the standard, a drum mounted upon one end of the shaft, a friction clutch operatively engaging said drum and having a lever, the clutch operating to frictionally engage the drum upon a movement of the lever in one direction but operatively disengaging it from the drum upon a movement of the lever in the other direction, frictionally operated means permitting free upward movement of the standard but locking the standard in a raised position and resisting downward movement thereof, manually operable means for gradually releasing the frictional engagement between said frictionally operated means and the standard to permit depression of the standard, and a stop carried upon the base against which the lever bears when the lever has been raised to a predetermined extent, said stop preventing the further rotation of the friction clutch and lever with the corresponding drum and acting as a fulcrum whereby the lever may be turned to open the clutch and permit the downward movement of the standard.

In testimony whereof I hereunto affix my signature.

THOMAS R. HOLLAND.
